FIG. 2.

Ralph E. H. Pomeroy
by Dennis S. Wolcott Atty

UNITED STATES PATENT OFFICE.

RALPH E. H. POMEROY, OF CANTON, OHIO.

PULVERIZING APPARATUS.

Application filed November 19, 1921. Serial No. 516,380.

To all whom it may concern:

Be it known that I, RALPH E. H. POMEROY, residing at Canton, in the county of Stark and State of Ohio, a citizen of the United States, have invented or discovered certain new and useful Improvements in Pulverizing Apparatus, of which improvements the following is a specification.

In applications Serial Nos. 393147 and 10 474079, filed respectively June 30, 1920, and June 1, 1921, are described and claimed improvements in pulverizing mills of the class or type embodying a revoluble drum and balls or other hard bodies. The improvements set forth in said applications provide for directing currents of air through perforations in the periphery of the drum and the loose mass consisting of pieces of friable material and the balls or other bodies. In 15 the operation of the improved mill it has been found that when a sufficient quantity of air at a sufficient rate of flow to effect an efficient removal of the material which has been reduced to the desired degree of fineness, is employed, coarser particles will also be withdrawn from the mass and carried 20 out of the drum, so that in many cases it is desirable to effect a grading of the material carried from the drum.

30 And further, it has been found in the operation of this type of mill the bulk of the charge consisting of the material to be treated and the balls will be found in the quadrant between the planes coincident with 35 the horizontal and partial diameters of the drum, although portions will extend beyond these planes, the greatest depth of the charge being generally found adjacent to the plane passing through the vertical diameter and 40 the charge will taper or decrease in depth from this plane to a point above the plane coincident with the horizontal diameter, a distance dependent upon the speed of rotation of the drum. In the construction shown 45 in the applications above referred to, provision is made for introducing air currents through the entire body of the charge, but it has been found in practice that with currents of sufficient strength to effect a removal of 50 the pulverized material from the thicker portions of the mass, materials which have not been sufficiently reduced will be carried out of the reducing areas or prevented from entering such reducing areas.

55 The object of the improvement claimed

herein is to provide for the introduction of the air currents to such portions of the charge as become loosened up and therefore more easily penetrable, such loosening of the charge occurring in the operation of the 60 mill as the charge is carried to and moved beyond a plane coincident with the horizontal diameter of the drum. By thus limiting the action of the air currents to the upper and less compacted portion of the charge, 65 it will be found that less quantities of air moving at a lower rate will act to efficiently remove material which has been pulverized to the desired degree of fineness.

It is a further object of the invention to 70 provide for a separation of the particles removed from the charge in accordance with the relative degree of fineness before they have been removed from the mill. The invention is hereinafter more fully described 75 and claimed.

In the accompanying drawings forming a part of this specification, Fig. 1 is a sectional elevation of a mill embodying the improvements described and claimed herein and Fig. 80 2 is a transverse section of the same.

The improved mill consists of a rotatable shell 5 having its ends secured to heads 6 provided with trunnions 7, one or both of which are made hollow for the feed of material to be ground into the shell 5. The trunnions are mounted on fixed bearings 8 and the shell is driven by a pinion 9 engaging a gear wheel 10 secured to one of the heads of the shell. The material to be 85 treated can be fed in through either one or both of the trunnions 7 by any suitable means known in the art, preferably such as shown and described in application Serial No. 474079, above referred to. A suitable 90 quantity of loose grinding material or devices, such as metal balls, cobble stones, rods or bars of hard material, are charged into the shell or drum and operate to pulverize the material by impact and rubbing. For 95 convenience the term "balls" will be used as a generic term including thereunder any and all devices usually employed in such a mill.

The shell 5 is enclosed by a casing 12 105 closely fitting against the shell but not with sufficient closeness to prevent the free rotation of the shell and provided with enlargements 13 and 14 thereby forming chambers 15 and 16. The enlargement 13 is so 110

located as to extend from a plane approximately coincident with a horizontal diameter of the drum along for a suitable distance, as for example, a little farther than the material would be carried in the rotation of the drum above this horizontal plane. In other words the chamber 13 preferably extends circumferentially from about the point where the charge in the shell begins to loosen up to a point a little beyond that at which the elements of the mass move away from the surface of the shell. This chamber is provided with an air inlet, which in case air at a pressure above atmospheric is employed, is connected to a fan or other air compressor. The other enlargement 14 extends preferably for about one-fourth of the circumference of the shell and is located so that the air after passing from the charge can escape through perforations in the shell into the chamber 16 from whence it is carried by any suitable means to the point of use. The periphery of the shell is perforated and the perforations preferably communicate with passages 17 formed in longitudinal liners 18 extending the full length of the shell. These liners are preferably constructed as shown and described in the application Serial No. 474079. As is well known in the art, the portions of the charge in a mill of this type lying in the quadrant between planes coincident with the vertical and horizontal diameters of the drum will be held closely in contact by the combined action of gravity and centrifugal force, and as soon as the charge passes above a plane approximately coincident with the horizontal diameter of the drum, gravity will act in a direction to cause a movement of the elements of the charge out of contact with each other and the inner surface of the drum, and the material will fall inwardly and roll down the inner surface of the charge to the lowest portion of the drum. It will be understood that this loosening up is progressive from a plane approximately coincident with the horizontal diameter of the drum and this portion of the mass is therefore more readily penetrable by the air currents. It is preferred that the passages directing the air into the drum should be arranged so that the air will enter the material in a direction at an angle to the radii of the drum and preferably in a direction opposed to the direction of rotation of the shell. As the air currents escape from the charge laden with pulverized material, they will sweep down along the entire surface of the charge and then up around the inner surface of the shell in a circular path. As the air currents carrying the pulverized material move in this circular path, they will flow across the passages 17 which have been brought by the rotation of the shell into communication with the outlet chamber 16, and on account

of the difference between the pressure in the shell and chamber, some of the air will flow through the passages; these passages being, as before stated, at an angle to the radii of the drum, will also be at a very acute angle to the direction of circular movement of the air in the shell so that in order to pass through these passages, the direction of movement of the air is abruptly changed, only the very fine particles whose size will be dependent upon the rate of movement of the air, will pass out through these passages into the chamber 16. The heavier particles will by reason of their momentum continue along in their original direction of movement and will be brought back to the pulverizing or reducing zone.

It will be understood that this outer casing may be adjustable circumferentially as described and shown in application Serial No. 474079, so as to change the position of the inlet chamber with reference to the charge within the drum or shell. In order to insure the circular or cyclonic movement of the air after escaping from the charge, the casing may be so adjusted that the inlet chamber will be in communication with some of the passages 17 after their discharge ends have passed a short distance beyond the upper end of the mass in the shell. The movement of air from these unswerved passages will sweep down along the inner surface of the charge and restore currents which have been diverted in passing through the charge to desired directions of movement.

As is well understood by those skilled in the art, the most effective reduction is effected while the elements of the charge are rolling or sliding down the inner surface of the mass and that reduction or pulverization over the entire inner surface is effected. It is characteristic of the improved manner of introducing the air currents, that the pulverized material is withdrawn from the inner portions of the charge, while in a condition facilitating such separation, and that by causing the currents to traverse the surface of the charge, the pulverized material is carried away from the area of most efficient reduction.

The circular or cyclonic movement of the air after escaping from the charge may be insured by arranging an air inlet chamber 19 in the rear (relative to the rotation of the shell) of the outlet chamber 16. When located as shown, each passage 17 will be brought into communication with the chamber after passing beyond the outlet chamber and the air entering through such passage will flow in the same direction as the air circulating in the shell. It will be understood that the air will enter this chamber 19 and flow through the passages under the pressure conditions ensuring cyclonic movement of the dust laden air. If air under

pressure is supplied to inlet chamber 15 it will be supplied to chamber 19 under pressure. Provision is made for the removal of any pulverized material collecting in the 5 lower portion of the outlet chamber 16 by connecting the latter to the chamber 19 by a valved pipe 20. The flow of air to the auxiliary chamber 19 may be regulated by a valve or damper 21.

- 10 It will be understood that the circumferential position of the outlet chamber is not material so long as it is separated a substantial distance from the outlet chamber and the inlet ends of the passages in communication with the outlet chamber are not covered by any portion of the charge. It is preferred, however, that the outlet chamber be so located that there will be a substantial travel of the air after passing from the 20 charge and preferably in a circular path. The currents of air employed for removing reduced particles from the charge are produced by maintaining differences of pressure between the inlet and outlet chambers by 25 any suitable means known in the art, as for example, by connecting the outlet chamber 14 to an exhaust fan as shown in Fig. 1.

I claim herein as my invention:

1. A pulverizing apparatus having in 30 combination a rotatable shell having a perforated periphery, balls adapted to move freely in said shell, means for maintaining a difference in the pressure of air between such predetermined points of the shell as 35 will cause currents of air to flow through the shell, the air entering and leaving the shell through the peripheral perforations.
2. A pulverizing apparatus having in combination a rotatable shell having a per- 40 forated periphery, balls adapted to move freely in said shell, a casing having outlet and inlet chambers with which the perforations in the shell are brought into communication successively by the rotation of the shell, and means for maintaining a difference 45 of fluid pressure between said chambers and thereby cause a flow of air through the shell.
3. A pulverizing apparatus having in combination a rotatable shell having a per- 50 forated periphery, balls adapted to move freely in said shell, a casing having inlet and outlet chambers with which the perforations in the shell are brought into communication successively, means for maintaining 55 a difference of fluid pressure between said chambers whereby a flow of air through said chambers is maintained, and means for abruptly changing the direction of flow of air after passing through the charge in the shell.

4. A pulverizing apparatus having in combination a rotatable shell provided with passages extending inwardly from the periphery of the shell and provided with ports

arranged to discharge air flowing there- 65 through in directions at an angle to the radii of the shell, and a casing having inlet and outlet chambers with which the outer ends of said passages are brought into communica- 70 tion successively on the rotation of the shell.

5. A pulverizing apparatus having in combination a rotatable shell provided with passages extending inwardly from the periphery of the shell and provided with ports 75 arranged to discharge air flowing there- through in directions at an angle to the radii of the shell, an inlet chamber with which the passages are brought into communication in succession by the rotation of the shell 80 and so located that such communication is established as the charge approaches the limit of the upward movement of the charge in the shell and an outlet chamber so spaced from the inlet chamber that the passages 85 are brought into communication therewith, subsequent to the movement of the pas- sages from the charge.

6. A pulverizing apparatus having in combination a rotatable shell provided with 90 passages extending inwardly from the periphery of the shell and provided with ports arranged to discharge air flowing there- through in directions at an angle to the radii of the shell, a casing having inlet and outlet 95 chambers with which the outer ends of the passages are brought into communication on the rotation of the shell and an auxiliary in- let chamber so constructed that the pas- sages will be brought into communication 100 therewith after passing out of communica- tion with the outlet chamber.

7. A pulverizing apparatus having in combination a rotatable shell provided with 105 passages extending inwardly from the pe- riphery of the shell and provided with ports arranged to discharge air flowing there- through in directions at an angle to the radii of the shell, a casing having inlet and outlet chambers with which the outer ends of the 110 passages are brought into communication on the rotation of the shell and an auxiliary inlet chamber so arranged that the passages will be brought into communication with the outlet chamber, and a connection be- 115 tween the outlet chamber and the auxiliary inlet chamber.

8. A pulverizing apparatus having in combination a casing, a rotatable shell hav- 120 ing openings in its periphery and means for causing the flow of currents of air through the casing and shell in directions at an angle to the axis of the casing and shell.

In testimony whereof, I have hereunto set 125 my hand.

RALPH E. H. POMEROY.
